UNITED STATES PATENT OFFICE.

JOHN KENNER, OF HERRIN, ILLINOIS.

AUTOMATIC SWITCH.

Application filed December 30, 1921. Serial No. 525,585.

To all whom it may concern:

Be it known that I, JOHN KENNER, a citizen of the United States, residing at Herrin, in the county of Williamson and State of Illinois, have invented new and useful Improvements in Automatic Switches, of which the following is a specification.

This invention relates to switches, and has particular reference to mine switches, which must be opened and closed in quick order to allow the haulage motor to pursue a predetermined course, different from the course pursued by the train of cars, from which the haulage motor is uncoupled just prior to its approach of the switch, thus allowing the train of cars to pass over the main line or into a siding, depending upon the course pursued by the haulage motor, and more particularly the manner in which the switch is actuated. The chief characteristic of the present invention resides in the provision of means carried by the haulage motor, which can be set to automatically actuate the switch in the manner and for the purpose above set forth, the switch being constructed so that it can be actuated from either side of the trackway to permit the haulage motor and the uncoupled train of cars to pursue different and definite courses. The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views and where-

40 in:—
Figure 1—is a plan view of the switch and its operating levers.

Figure 2—is a sectional view taken on line 2—2 of Figure 1.

45 Figure 3—is a similar view taken on line 3—3 of Figure 1.

Figure 4—is a side elevation of the haulage motor.

50 Figure 5—is a top plan view thereof. Referring to the drawings in detail, and more particularly to Figure 1, 10 indicates the main track and 11 the siding, the movable switch points being indicated at 12 and pivoted as at 13. These switch points are 55 operatively connected with the bridle 14 movable transversely of the trackway, whereby

the switch points are simultaneously movable to either open or close the switch in a manner to be hereinafter more fully described. While the switch is adapted to be automatically actuated by motor carrying means, the bridle projects an appreciable distance beyond one side of the track, and is associated with a manually operable lever 15, whereby the switch can be manually actuated in the case of emergency. Extending across the trackway is a plurality of closely associated metallic bars or strips 16 which are employed to prevent large pieces of coal or other articles from lodging in positions which would interfere with the operation of the switch, and at the same time provide a walk whereby the track could be easily traversed at this particular point.

Levers 17 and 17' are arranged at the opposite sides of the trackway, these levers being pivoted at points between their ends as at 19, upon one of the metallic bars 16. Arranged substantially parallel with each lever is a comparatively short lever 20, the corresponding extremities of said levers being operatively connected as at 21 with the adjacent ends of the bridle 14. This bridle is constructed with cushioning springs 22. The opposite ends of the short levers 20 are 85 connected with the main levers 17 and 17' through the instrumentality of links 23, the construction and arrangement of parts being such that the short levers 20 function to equalize the throw of the switch regardless 90 of the length of the main levers 17 and 17'. Carried by each of the main levers, adjacent the opposed ends thereof, are curved extensions 24, the latter being curved in a direction of the trackway and adapted to be 95 engaged by the means carried by the haulage motor to actuate the levers in a manner and for a purpose to be hereinafter described.

Links 25 provide the connections between 100 the corresponding ends of the main levers 17 and 17', and the auxiliary levers 26 and 26', the said links being pivotally connected with the adjacent ends of said auxiliary levers as illustrated. The auxiliary lever 26 105 forms in reality a continuity of the main lever 17 and extends along the main track 10, while the auxiliary lever 26' forms a continuity of the main lever 17' and extends along the siding 11. Each of the auxiliary 110 levers is fulcrumed as at 27 midway of its length, while the free end of each auxiliary

lever is provided with a curved extension 28. The curved extensions are arranged and used in the same manner as the curved extensions 24 carried by the main levers above 5 referred to.

Bridging two of the ties 29 at an appropriate distance away from the switch on the main track 10 are arcuate-shaped plates 30, these plates being arranged at the opposite 10 sides of the main line for a purpose to be hereinafter set forth. A similar plate 31 bridges the ties 32 at one side of the main line in juxtaposition to the auxiliary lever 26, while another plate of the same character 15 indicated at 33 bridges the ties 34 at one side of the siding 11 and in juxtaposition to the auxiliary lever 26'.

The haulage motor indicated generally at 35 is of any well known construction, this 20 motor being equipped with means capable of being set to actuate the switch from either side of the trackway, to open or close the switch to the main line or the siding, depending upon the particular course which 25 the haulage motor is to pursue, and in contradistinction to the course adapted to be pursued by the train of cars. It is of course understood that in mine switches, the haulage motor 35 is uncoupled from the train of 30 cars just prior to its approach of the switch, and it is necessary to actuate the latter in order to allow the haulage car to pass over the main line or onto the siding, to permit the train of cars to pass over the particular line 35 or track not traversed by the haulage motor. For this purpose, I equip the haulage motor 35 with a transversely disposed shaft 36, which is journaled in suitable bearings 37. Carried by the shaft 36 adjacent one end 40 thereof is a bell crank lever, one branch 38 of which is associated with the adjacent terminal of a connecting rod 39, the latter being operatively connected with the manually 45 controlled lever 40. Depending from the remaining branch 38' of the bell crank lever is the switch actuating element 41, the latter being slidable through suitable guides 42, and carrying at its lower end a roller 43. The switch actuating element is connected 50 with the branch 38' of the bell crank lever by means of a link 44. Projecting from the shaft 36 adjacent its opposite end is an arm 45, and this arm projects from the shaft in a direction directly opposite to the direction 55 in which the branch 38' of the bell crank lever extends from said shaft. A second switch actuating element 46 depends from the arm 45 and is operatively connected therewith through the instrumentality 60 of a link 46'. This actuating element slides through suitable guides 47 and is also equipped with a roller 48 at its lower end. The manually operated lever 40 is fulcrumed 65 as at 49 and is designed to engage flanges 50 and 51 projecting from one side of a resili-

ent frame 52. The relative arrangement of the arm 45 with regard to the branch 38' of the bell crank is such, that when the lever 40 is moved in one direction, the shaft 36 is rotated to move the switch actuating element 70 41 downwardly into an active position, at which time the switch actuating element 46 is elevated. When the manually operated lever 40 is shifted in an opposite direction, the switch actuating element 46 at the opposite side of the motor is lowered, while the switch actuating element 41 is simultaneously elevated. The frame 52 is as above 75 stated, of a resilient nature, so that when the manually operated lever 40 is moved in the direction of its neutral position through the operation of one or the other of the switch actuating elements, the resilient frame functions to assist the lever in its return to normal position, while the flanges 51 and 52 80 retain the said lever 40 in its upright position.

In practice, assume that the haulage motor together with a train of cars is approaching the switch over the main line 10, and it is 90 desired to have the haulage motor continue over the main line, and the train of cars moved onto the siding 11. The manually operable lever 40 is moved forwardly after the motor has passed the arcuate-shaped 95 plates 30, these plates being arranged approximately one-hundred feet away from the switch. Incident to the movement of the lever 40 in a forward direction, the switch actuating element 41 is lowered 100 and as above stated, the switch actuating element 46 simultaneously elevated, so that the switch is actuated from one side of the trackway. With the switch actuating element 41 in its lowered 105 active position, it contacts the curved extension 24 carried by the adjacent end of the main lever 17, thereby shifting the lever upon its fulcrum and setting the switch points for the main line 10. It is of course 110 understood that the haulage motor is uncoupled from the train of cars at some point between the arcuate-shaped plates 30 and the switch, and moves faster than the train of cars, so that as it passes over the switch, 115 it sets the latter in a manner just described to allow the haulage motor to continue its course over the main line. When the lever 17 is shifted in a manner just stated, the curved extension 24 carried by the opposite 120 end of this lever is moved to a position in close proximity to the main line, so as to be engaged by the switch element 41 at the proper time. As the motor passes over the switch bringing the element 41 into contact 125 with the latter mentioned curved extension 24, the lever 17 is again shifted in a reverse direction to close the switch to the main line, and open the switch to the siding 11. Consequently, when the train of cars approaches 130

the switch, the latter is set to direct the train of cars onto the siding 11. After reversing the movement of the lever 17 to close the switch to the main line, the actuating element 41 passes over the arcuate-shaped plate 31, thus elevating the actuating element 41 to its inactive position, and at the same time automatically moving the lever 40 to its neutral position. Incident to the movement of the lever 17 to close the switch to the main line, the auxiliary lever 26 is simultaneously shifted upon its fulcrum to position the curved extension 28 thereof in close proximity to the main line to be engaged by the switch actuating element 41 upon the return of the haulage motor 35. Just prior to the return of the motor over the main line, the lever 40 which had been previously returned to neutral position, is again shifted to lower the actuating element 41 to an active position. Consequently, when the motor starts back over the main line, the actuating element engages the curved extension 28 of the auxiliary lever 26, shifting the said lever on its fulcrum to the position illustrated by dotted lines in Figure 1. When the auxiliary lever 26 is thus shifted, it imparts movement to the main lever 17, shifting the latter to a position to open the switch, whereby the haulage motor can continue its movement over the main line to its starting position.

The operation of the mechanism at the opposite side of the track is identically the same as that just described in connection with the main lever 17 and the auxiliary lever 26, except that the lever 17' and the auxiliary lever 26' are actuated by the switch actuating element 46 at the opposite side of the haulage motor. For instance, should it be desired to have the haulage motor enter the siding 11 instead of moving over the main track beyond the switch, the lever 40 is moved rearwardly, thereby lowering the switch actuating element 46 to its active position and elevating the actuating element 41 to its inactive position. When the actuating element 46 contacts the curved extension 24, carried by the adjacent end of the lever 17', this lever is shifted to actuate the switch points with a view of opening the switch to the siding 11. As the haulage motor enters the switch 11 the curved extension 25 carried by the opposite end of the lever 17', is engaged by the actuating element 46 having been shifted to a position in the path of movement of this element incident to the opening of the switch to the siding. When the latter mentioned extension 24 is engaged by the trip element 46, the movement of the lever 17' is reversed, closing the switch to the siding 11 so that the train of cars will continue along the main line. After having engaged the curved extension 24, the switch element 46 passes over the arcuate-shaped

plate 33, thereby elevating the actuating element to its inactive position, and automatically returning the lever 40 to neutral position. Incident to the movement of the lever 17' to close the switch to the siding 11, the auxiliary lever 26' is shifted to position the curved extension 28 thereof in the path of movement of the element 46, so that the switch can be actuated upon return of the haulage motor, to set the switch so that the motor can pass from the siding back onto the main line. For this purpose, the lever 40 is again shifted rearwardly, thereby lowering the actuating element 46, and when the haulage motor starts back over the siding 11, the element contacts the curved extension 28 of the auxiliary lever 26', and shifts this lever together with the lever 17' in a manner to open the switch to the main line. After having actuated the auxiliary lever 26 in this manner, the actuating element 46 again passes over the curved plate 33 and returns said element together with the manually operated lever 40 to their normal positions. Should either of the actuating elements 41 or 46 be in their active positions, after the haulage motor has passed over the switch on its return to the line, it passes over one or the other of the plates 30 so that the parts are automatically returned to normal position. The mechanism is simple in construction, and very positive in operation, and after placing the operating lever in either of its active positions, it does not require the attention of the operator as it is automatically returned to normal position after the switch has been properly actuated.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim is:

1. In a railway switch operating mechanism, the combination with a main track and a siding, of levers arranged at the opposed sides of the track, and fulcrumed at points in their length, contact members carried by each lever adjacent its ends, equalizing members operatively connected with the aforementioned levers and with the switch elements, car carried means operable to selectively actuate either of the first mentioned levers, whereby the switch can be opened and closed at predetermined intervals to either the main track or said siding, the means arranged along the tracks for automatically returning the car carried means to normal position.

2. In a railroad switch operating mechanism, the combination with a main track and a siding, of levers arranged at the opposed

2

sides of the track and fulcrumed at points in their length, contact members carried by each lever adjacent its ends, equalizing members operatively connected with the aforementioned levers and with the switch elements, car carried means operable to actuate either of the first mentioned levers, whereby the switch can be opened and closed at predetermined intervals to either the main track or said siding, auxiliary levers pivotally connected with the aforementioned levers, curved contact members carried by the

auxiliary levers and adapted to be shifted into the path of movement of the car carrying means incident to the opening and closing of the switch, and means arranged along the tracks for automatically returning the car carried means to normal position just prior to passing the latter mentioned contacts of the auxiliary levers for the purpose specified. 15 20

In testimony whereof I affix my signature.

JOHN KENNER.
